(57) **CLAIM**

The ornamental design for a case for an electronic communications device, as shown and described.

DESCRIPTION

FIG. 1 is a front perspective view of a case for an electronic communications device showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a 9-9' cross sectional view thereof;

FIG. 10 is a 10-10' cross sectional view thereof;

FIG. 11 is a perspective view before a card and the electronic communications device are received in the case; and,

FIG. 12 is a perspective view with the card and the electronic communications device received in the case.

The broken line showing cross section designation lines, a card and an electronic communications device is included for the purpose of illustrating use and environment and forms no part of the claimed design.

The back plate has a recessed area for storing a card such as credit/debit card, driver license, identification card or the like.
